UNITED STATES PATENT OFFICE.

WADE B. THOMPSON, OF DETROIT, MICHIGAN.

T-HEAD CONSTRUCTION.

1,245,821.

Specification of Letters Patent.

Patented Nov. 6, 1917.

Application filed July 5, 1916. Serial No. 107,722.

To all whom it may concern:

Be it known that I, WADE B. THOMPSON, a citizen of the United States, residing at Detroit, in the county of Wayne and State 5 of Michigan, have invented new and useful Improvements in T-Head Constructions, of which the following is a specification.

This invention relates to a T-head construction and has for its primary object to 10 provide a T-head having the inherent properties of attaching itself to surfaces of certain characteristics.

An object of the invention is the novel manner of associating the magnets and supporting them in the frame so that the greatest 15 amount of magnetic traction can be accomplished.

Besides the above my invention is distinguished in the use of a plurality of permanent magnets having their poles so arranged as to form the straight edge of the 20 T-head.

With these and other objects in view the invention will be better understood from 25 the following detailed description taken in connection with the accompanying drawing, wherein

Figure 1 is a top plan view of the head with the plate removed.

Fig. 2 is a cross sectional view thereof.

Fig. 3 is a longitudinal sectional view, and

Fig. 4 is a cross sectional view of a modified form of my invention.

Referring to the drawing the T-head consists of a frame 1 constructed to have a body 2 and three parallel limbs 3, 4 and 5 projecting laterally from the body 2. The limb 3 is rigidly connected to the body 6 of the T-square. Filling the spaces between the limb 3 and the limbs 4 and 5 are two sets of permanent bar magnets 7 and 8, each bar magnet 9 of which being formed with a head 10 through all of which with the exception of the end magnet 11 of each set passes a bolt 12 having screw threaded engagement with the magnet 11. From this arrangement it will be seen that all of the magnets of a set are rigidly connected together and for the purpose of preventing the grouped bar magnets from movement I provide the securing elements 13 in the form of screws mounted in the frame and having screw threaded engagement with certain of the bar magnets.

To complete my invention I provide

plates 14 detachably secured to the frame by the screws 15 and inclosing all of the bar magnets with the exception of the poles thereof that form the straight edge for the 60 head.

If found advantageous in practice the end magnet of each set may have a tongue and groove connection 16 with the limbs of the head.

In the modified form of my invention each bar magnet 17 is in the form of a U so as to have its north and south poles arranged adjacent each other so that the tractive effect may be increased.

At this point I wish to call attention to the fact that I do not care to be limited to the exact arrangement of the poles of the magnet as the polarity of the poles may be identical or reverse depending entirely upon 75 the purpose to which the invention is put.

In this particular showing I have shown a drawing board 18 having secured to its edges a strip 19 of magnetic material, but I wish it to be understood that the T-square 80 may be used directly on iron structures that are being erected.

From the foregoing description taken in connection with the accompanying drawing, it should be apparent that I provide a device 85 which is admirably adapted for the purpose for which it is intended, that the device is simple, durable and efficient of construction and may be manufactured and sold at a comparatively low cost.

What I claim is:—

1. In a device of the character described, a series of magnetic elements, a headed screw passing through a hole in said magnetic elements, the far end magnet having a hole 95 therein threaded to engage the screw threads of the screw, a body having a recess therein, and screws engaging holes in said body and screw threaded into certain of the magnetic elements whereby said series of magnetic 100 elements are secured within the recess.

2. In a device of the character described, a body having a recess therein, a magnetic element secured within said recess, a groove formed in said magnetic elements, a tongue 105 formed on said body within said recess and engaging said groove whereby the magnetic element prevents the body from warping.

3. In a device of the character described, a series of magnetic elements, a headed 110 screw passing through holes in said magnetic elements, the far end magnetic element

having the hole therein threaded to engage the screw threads of the screw, a body having a recess therein, means for securing said magnetic elements within said recess, a groove formed in one of said magnetic elements, and a tongue formed on said body within said recess and engaging said groove whereby said magnetic element prevents the body from warping.

10 4. In a device of the character described, a series of magnetic elements, a headed screw passing through holes in said magnetic element, the far end magnetic element

having the hole therein threaded to engage the screw threads of the screw, a body having a recess therein, screws engaging said holes in said body and screw threaded in certain of said magnetic elements within said recess, a groove formed in one of said magnetic elements, and a tongue formed on said body within said recess and engaging said groove whereby the magnetic element prevents the body from warping.

In testimony whereof I affix my signature.

WADE B. THOMPSON.
